United States Patent Office

Des. 175,752
Patented Oct. 11, 1955

175,752

DINNER PLATE OR SIMILAR ARTICLE

Winslow Anderson, Trenton, N. J., assignor to Lenox
Incorporated, Trenton, N. J., a corporation of New
Jersey

Application May 5, 1955, Serial No. 35,812

Term of patent 7 years

(Cl. D44—15)

FIG. 1.

FIG. 2.

FIG. 3.

Figure 1 is a top plan view of a dinner plate or similar article showing my new design;

Figure 2 is a side elevational view; and

Figure 3 is a vertical sectional view thereof.

I claim:

The ornamental design for a dinner plate or similar article, as shown.
